UNITED STATES PATENT OFFICE.

FRANK H. LINDENBERG, OF COLUMBUS, OHIO.

TANK.

1,060,609.

Specification of Letters Patent.

Patented May 6, 1913.

Application filed January 26, 1912. Serial No. 673,649.

To all whom it may concern:

Be it known that I, FRANK H. LINDENBERG, citizen of the United States, residing at Columbus, in the county of Franklin and 5 State of Ohio, have invented certain new and useful Improvements in Tanks, of which the following is a specification.

My invention relates to tanks and is particularly designed as an improvement in 10 flushing tanks calculated to produce an extremely simple and compact structure with a maximum simplicity of formation.

It is further aimed to provide a structure having a high degree of rigidity and this 15 is desirably effected by the provision of a bracing element for the open top of the tank. This may be in the nature of a separate element or may be formed integrally with the tank body. It is desirable in the formation 20 of this bracing element to have it of such a structure that it will constitute a guide for a top constructed to slide thereon and in addition will be provided with depending fingers constructed and operable to retain 25 the lining of the tank in its proper position, such fingers being further peculiarly formed to assist in supporting and bracing the top slid there-over.

In the construction of my tank, it may be 30 formed entirely of one piece or the body may be formed of one piece and the bracing element by an independent piece. The lining of the tank is desirably spaced from the tank itself by the provision of a corrugated 35 moisture-proof piece of any desired material.

The preferred embodiment of my invention is shown in the accompanying drawings, in which similar character of reference designate corresponding parts, and in which—

40 Figure 1 is a perspective view of my improved tank showing the body portion formed in one piece and showing a separate framework carried upon the open top of said body portion in a manner to rigidly 45 brace the same. Fig. 2 is a perspective view of a modified form of tank wherein the tank and the bracing structure are all formed in one piece, Fig. 3 is a cross section of the tank shown in Fig. 1 with the top mounted 50 thereon, Fig. 4 is a cross section of the tank shown in Fig. 2 with the top mounted thereon, Fig. 5 is a plan view of the blank of which the body portion shown in Fig. 1 is formed, and Fig. 6 is a plan view of the 55 blank of which the structure shown in Fig. 2 is formed.

In the drawings, referring to the form shown in Figs. 1, 3 and 5, it will be seen that the blank comprises the front piece 1, rounded corners 2, sides 3 and pieces 4 60 which join to form the back. The portion 5 comprises the bottom and the dotted line shows the extent of the surplus material in the blank of the bottom. The formation of the blank shown in Fig. 5, makes it apparent 65 that the tank formed thereby, will be open at its upper end and for the purpose of rigidly bracing this open end, I provide a skeleton framework formed of an outer rim 6 of substantially L-shape, a plurality of 70 cross braces 7 desirably integrally formed with the said rim and a plurality of L-shaped fingers 8 extending inwardly in the same plane with the upper edge of the rim 6 and then downwardly within the tank. 75 The form and size of these fingers is especially calculated to permit them to serve as retaining fingers for an inner lining 9 which is desirably spaced from the interior wall 80 of the body of the tank by a moisture-proof material, as hitherto stated. It will be understood that the L-shaped formation of the rim 6 causes the same to serve as an efficient 85 guide for a cover 10 having a hook-shaped flange 11 formed on three sides thereof.

The structure shown in Figs. 2, 4 and 6 is an example of a preferred manner of forming a tank of this type entirely from one piece of material with the exception of the inner lining. In this structure and referring to the blank shown in Fig. 6, the face is designated 12, corners 13, sides 14 and portions 15 which unite to form the back. The base is designated 16 and the dotted lines thereof show the surplus material 90 necessary to effect a proper joining. The upper bracing element is, in this case, formed integrally with the blank and is designated 17, being spaced from the face 12 by surplus material 18 calculated to permit of the formation, with the surplus material 19, of a bracing rim 20. This rim serves to reinforce the top of the tank in the same manner that the same is reinforced by the rim 6 in the structure shown in Figs. 100 105 1, 3 and 5 and to likewise serve as a guide-way for the top to be applied thereto. The portion 17 of this blank is further stamped out as at 21 to form reinforcing strips 22 and depending fingers 23 effective to retain 110 the inner lining 24 in proper position. The stamping out of these pieces is effective to

leave a practically open top for the insertion of the fittings and there is thus produced the effect of an open top with an integral bracing structure. Mounted upon this top 5 and slid thereon in the same manner as in the previously described structure, is a cover 25.

It will be seen that I have provided a structure of tank which is readily made and 10 combines with this simplicity a certain rigidity largely the result of the bracing element at the top and that there are various other features resulting from this simplicity and this bracing element, rendering the tank 15 extremely desirable.

What I claim, is—

1. A sheet metal tank having an open top, an independent bracing element for said top portion, an independent inner receptacle, 20 and means carried by the upper portion of said tank for maintaining said inner receptacle in spaced relation to said tank.
2. A sheet metal tank having an opening in the top, bracing means spanning said top, 25 an inner receptacle, and means carried by

said bracing means for maintaining said inner receptacle in spaced relation to said tank.

3. A tank formed with an open top, an independent bracing framework, a lining, 30 and fingers on said framework for maintaining said lining in spaced relation to said tank.

4. A tank comprising a receptacle having an open top, a framework bracing said top, 35 depending fingers on said framework, and an inner lining held spaced from said tank by said fingers.

5. A tank comprising a receptacle having an open top, a framework bracing said top, 40 a lining, L-shaped retaining fingers on said framework and for said lining, and a slideable top, said fingers being constructed to partially support said top.

In testimony whereof I affix my signature 45 in presence of two witnesses.

FRANK H. LINDBERG.
